OTHER PUBLICATIONSLMA Supreme Airway, Chinook Medical Gear Inc, Product No. #01621PA, [<https://www.chinookmed.com/01621pa/lma-supreme-airway.html>], accessed Jan. 21, 2019.*Primary Examiner* — Darlington Ly(74) *Attorney, Agent, or Firm* — Tech Valley Patent, LLC; John Pietrangelo**(57) CLAIM**

The ornamental design for an intubation device, as shown and described.

DESCRIPTION

FIG. 1 is a perspective view of an intubation device showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines in the drawings illustrate portions of the intubation device that form no part of the claimed design.
